UNITED STATES PATENT OFFICE.

DELPHIN B. COBB, OF BROOKLYN, NEW YORK.

TUBE-PACKING FOR SURFACE-CONDENSERS.

SPECIFICATION forming part of Letters Patent No. 334,512, dated January 19, 1886.

Application filed May 14, 1885. Serial No. 165,418. (No model.)

To all whom it may concern:

Be it known that I, DELPHIN B. COBB, of Brooklyn, in the county of Kings and State of New York, have invented certain new and 5 useful Improvements in Tube-Packings for Surface-Condensers, of which the following is a specification.

This invention has reference to an improved tube-packing for surface-condensers, by which 10 the tubes can be put in or taken out for the purpose of cleaning without injury either to the tubes, packing, or thimbles.

The invention consists of a condenser-head having recessed holes, tubes passing through 15 said holes, a packing between the tubes and the recessed holes, and a threaded thimble or gland having a conically-contracted and recessed outer end for being readily screwed into the condenser-head.

20 The invention consists, secondly, of a thimble or gland having an exterior screw-thread and a conically-contracted and recessed outer end.

In the accompanying drawings, Figure 1 25 represents an end view of a condenser-head with my improved tube-packing. Fig. 2 is a vertical transverse section through the condenser-head, showing two condenser-tubes with my packing. Figs. 3, 4, and 5 are respectively a vertical central section of the 30 blank for a thimble and a vertical central section and an end view of a finished thimble, and Fig. 6 is a vertical central section of a die for contracting the ends of the thimbles or glands.

35 Similar letters of reference indicate corresponding parts.

Referring to the drawings, A represents a metal condenser-head, which is provided with a series of holes that are cast or drilled in, said 40 holes being recessed or enlarged so as to form shoulders *a*. The condenser-tubes B B are guided in the holes of the condenser-heads by a suitable packing, *b b*, which is placed around the tubes so as to abut against the shoulders *a* of the recessed holes. The packing *b* is confined between washers *b'* at both ends, which may be made of any suitable material, so as to properly protect the packing, the inner washers preventing the packing from being 45 forced beyond the shoulders into the condenser, while the outer washers serve for taking up

the friction of the thimbles or glands C C, by which the packing is tightly applied to the tubes B B. The thimbles or glands C C are provided with exterior screw-threads and with 55 conically-contracted outer ends having recesses or notches *d d*, for being conveniently taken hold of by the operating tool. By screwing in the thimbles C C the packing is tightly compressed around the condenser-tubes. The 60 thimbles C C are made from a section of metal tubing, the outer end of which is conically contracted by suitable dies, as shown in Fig. 6. The die is provided with a central steel pin, between which and the inner wall of the 65 matrix an annular space is formed for receiving the cylindrical blank. The upper end of the center-pin is made conical, for imparting the required conical contraction to the end of the blank. When the blank is thus placed in 70 position, a drop-die having a conical cavity will contract that part of the blank above the matrix without upsetting that part of the blank in the matrix. After the blank is thus made conical at one end, the latter is recessed or 75 notched at diametrical points, so as to provide the recesses for being taken hold of by a screw-driver or other suitable tool. The cylindrical portion of the blank is then screw-threaded at its outer surface. 80

The object of making the thimbles with conical ends is to prevent the tubes from crawling or creeping in the condenser-heads any farther than the contracted ends of the thimbles, at which points they are effectually 85 stopped. When the thimbles are screwed home in the condenser-heads, the tubes will have a sufficient play between the conical ends of the thimbles, so as to give sufficient space for expansion, but limiting the crawling. The 90 packing can be readily adjusted from time to time by the thimbles, as they can be screwed home into the condenser-heads, as shown in Fig. 2, without being stopped by exterior collars, that would arrest the motion of the thimbles. 95

I am aware that different constructions of thimbles or followers have been proposed heretofore for compressing the packing of condenser-tubes and limiting the crawling or 100 creeping of the tubes. Among the more recent ones I refer to the patent granted to Joseph

S. Wilson, No. 221,435, dated November 11, 1879, in which the thimble or follower is provided with an exterior screw-threaded portion and a thickened inwardly-extending flange having recesses, whereby said flange may be adjusted by a suitable tool. This thimble or gland, however, is stopped by the exterior thickened end flange from being screwed into the condenser-head, so that the packing cannot be properly adjusted from time to time, as required.

In the patent granted to William E. Todd, No. 288,891, of November 20, 1883, the thimble or follower consists of an exteriorly-threaded brass tube having inwardly-bent lugs and notches. This follower is also stopped by the thicker end portion, so that it can only be screwed into the condenser-head up to the thicker end. By my thimble these objections are avoided, as the packing can be depressed from time to time for tightly packing the tubes, as the thimbles can be screwed home into the condenser-head to the entire depth of the threads of the recessed holes by means of the conically-contracted ends, which cannot abut against the condenser-head.

Another advantage is, that the thimbles can be made shorter, so as to save considerably in

material, while greatly increasing their convenience and economy for use.

Having thus described my invention, I claim as new and desire to secure by Letters Patent—

1. The combination of a condenser-head having recessed holes, condenser-tubes passing through said holes, suitable packing placed around the tubes, and threaded thimbles or glands having conically-contracted and recessed outer ends, substantially as set forth.

2. The combination of a condenser-head having recessed holes, condenser-tubes guided in said holes, suitable packing provided with end washers, and threaded thimbles or glands having conically contracted and recessed outer ends, substantially as set forth.

3. A thimble or gland for the tube-packing of surface-condensers, provided with an exterior screw-thread and a conically-contracted and recessed outer end, substantially as set forth.

In testimony that I claim the foregoing as my invention I have signed my name in presence of two subscribing witnesses.

DELPHIN B. COBB,
